UNITED STATES PATENT OFFICE.

BENJAMIN TURTON, OF NEWARK, NEW JERSEY, ASSIGNOR TO CRANE & CO., OF SAME PLACE.

BRIDLE-BIT.

SPECIFICATION forming part of Letters Patent No. 339,716, dated April 13, 1886.

Application filed November 19, 1885. Serial No. 183,335. (No model.)

To all whom it may concern:

Be it known that I, BENJAMIN TURTON, a citizen of the United States, residing at Newark, in the county of Essex, State of New Jersey, have invented certain new and useful Improvements in Bridle-Bits, of which the following specification is a full, clear, and exact description.

This invention relates more particularly to that class of bridle-bits in which a small or check bit is loosely connected with a larger bit or mouth-piece, to the cheek-pieces of which the driving-reins are attached.

Heretofore various means for connecting the check-bit with the mouth-piece or driving-bit have been devised or employed. For example, studs screwed into the mouth-piece or driving-bit so as to be within the horse's mouth have been fastened to the check-bit by ball-and-socket joints, or side pieces outside the horse's mouth, and provided with holes through which both bits pass, have served to link them together, or rings held in eyes on the driving-bit or mouth-piece have encircled the check-bit inside the horse's mouth, or eyes on the driving-bit or mouth-piece have received a bar on the under side of the check-bit.

The present invention has for its object to produce a neater, cheaper, more efficient, and generally better bit, and also particularly so to connect the driving-bit with the check-bit that the motions of the former will not disarrange the latter, and to secure greater freedom of motion or independent play between the two bits within desirable limits. When the driving-bit or mouth-piece is provided with eyes or rings which slide lengthwise of the check-bit, or of a bar attached to the same, it is evident that when the driving-bit is drawn to one side the pressure or pull upon the check-bit is no longer in the middle of the latter, but near one end, and the tendency is to pull down that end more than the other and to disarrange the check-bit or the straps connected with it. This shifting of the eyes lengthwise of the check-bit it is desirable to avoid. Entire independence of the two bits is not desirable, but within certain limits it is advanta-

geous to secure a greater freedom than the means heretofore used allow.

The invention consists, first, in a driving-bit or mouth-piece provided on its upper side with a raised bar, by means of which a sliding connection is made with the check-bit through one or more eyes fixed at or near the middle of the check-bit, so that no matter in what position the driving-bit or mouth-piece may be, the strain put upon the check-bit being applied through the eyes is always at the same part, and does not tend to pull down the ends of the check-bit unequally; second, in connecting the check-bit and driving-bit or mouth-piece together by means of a single eye traveling on a bar somewhat smaller than the eye, so that the bits cannot only slide past each other, but can be turned independently of each other through a considerable angle in practically all directions; and, third, in a special bit having the driving part or mouth-piece composed of three or more parts jointed together, the central link being provided with a raised bar, with which the check-bit is connected by a single eye on the under side of said check-bit. Under the first part of this invention any suitable means for making a sliding connection between the check-bit and the raised bar on the mouth-piece or driving-bit may be employed, provided the strain from the driving-bit is not transferred lengthwise of the check-bit when the former is slid lengthwise of the latter.

In the accompanying drawings, which form part of this specification, Figure 1 is a view of a jointed bridle-bit constructed in accordance with the invention, and Fig. 2 a view illustrating the application of a part of the invention to a stiff bit. Fig. 3 is a view of a modified form of central link for a three-part jointed mouth-piece.

The check-bit A, having the rings B at the end, is provided on the under side with an eye, C, by means of which it is connected with the raised bar D, on the upper side of the mouth-piece or driving-bit. This latter, as shown in Fig. 1, is composed of two side pieces, E, provided each with the usual check-piece, F, and jointed to the central link, G, which is provided with the raised bar D. This central

link may be of cast malleable iron, or it may be forged from iron or steel. The bar D is made thinner than the body of the link, so that it can be encircled by a comparatively small eye 5 on the check-bit. The eye is rather larger than the bar, so that it can turn thereon in all directions, as well as slide lengthwise of the same. Very little strain comes upon the bar D, the pull upon the driving bit or mouth-piece being mainly borne by the body of the central link, G. Practically the bar D curves 10 up slightly in the middle.

In use the check-straps are attached to the rings B, the driving-reins to the cheek-pieces 15 F. The connection of the check-bit A with the driving-bit or mouth-piece E G, by means of the eye C, fixed on the check-bit, and the raised bar D on the mouth-piece, the strain of the latter always comes upon the middle of the check-bit, whatever position the mouth-piece may 20 occupy. When the mouth-piece is pulled from side to side, the bar D slides in the eye C. The use of a single eye allows the driving-bit or mouth-piece to be turned independently of the check-bit. The length of bar shown suffices 25 to give a reasonable play to the check-bit and mouth - piece without interfering with the movements of the side pieces, E, independently of the central link, since practically it 30 does not or need not extend beyond the said link.

A central link, G", Fig. 3, may be used in place of the link G, Fig. 1.

In Fig. 2 an attachment in the form of a 35 plate, G', slotted to form the raised bar D, is secured to a stiff mouth-piece or driving-bit, H, by means of rings I, which are sunk in grooves in the driving-bit. The raised bar D may also be forged or cast on the driving-bit 40 or mouth-piece, or be otherwise attached to it.

The present invention is not limited to the precise construction shown; neither does it include the connection, with the check-bit, of a stiff driving-bit or mouth-piece in contradis-

tinction to a flexible or jointed one, the stiff bit 45 being shown as illustrating an obvious application of the invention or of part thereof.

Of course the invention does not include the various bits which have been heretofore devised or used, as pointed out in the first part 50 of this specification.

I claim as my invention—

1. An improved bridle-bit, consisting of a driving-bit or mouth-piece and a check-bit, the two pivotally or loosely connected together 55 by a device or connection, substantially as described, fixed to the middle of the check-bit, engaging a raised bar on the driving-bit, so that the strain from the driving-bit or mouth-piece comes always on the middle of the check-bit 60 and is borne equally by the check-straps at the two ends of the same in all positions of the driving-bit or mouth-piece, substantially as set forth.

2. An improved bridle-bit, consisting of a 65 driving-bit or mouth-piece and a check-bit, the two connected together by a raised bar on the driving-bit or mouth-piece, and a single eye on the check-bit, said eye encircling said bar and being adapted to turn thereon laterally to a limited extent, as well as to slide 70 lengthwise of the same, substantially as described.

3. The improved bridle-bit, consisting of a jointed mouth-piece or driving-bit having a 75 central link provided with a raised bar, and a check-bit provided with a single eye encircling said bar, on which it may slide and also turn laterally to a limited extent, said eye serving always to bring the strain or pull upon 80 the middle of the check-bit, substantially as described.

In testimony whereof I affix my signature in presence of two witnesses.

BENJAMIN TURTON.
